TYPEWRITER

Adolphus S. Dennis, Oakland, Calif., assignor to
Friden Calculating Machine Co., Inc., a corporation of California

Application December 30, 1941, Serial No. 424,960

10 Claims. (Cl. 197—17)

This invention relates to typewriters and is concerned more particularly with the provision of power operation of the type bars thereof.

It is a general object of the invention to provide an improved power-operated drive for the key bars of typewriters.

Another object of the invention is to provide power-driven mechanism of the character referred to which can be readily applied to existing typewriters.

Other objects and advantages of the invention will be apparent from the following description of a preferred embodiment thereof, as illustrated in the accompanying drawings, in which:

Figure 1 is a longitudinal sectional view showing the power drive mechanism as applied to a typewriter.

Figure 2 is a fragmentary elevational section of a unit of the power drive mechanism as positioned in Figure 1.

Figure 3 is a view similar to Figure 2 but showing the parts in position at the beginning of the downstroke of the key.

Figure 4 is a view similar to Figures 2 and 3 but showing the key drive unit at the end of its power-driven stroke.

Figure 5 is a view similar to Figures 2 through 4 showing the release of the key drive unit at the end of the key stroke.

Figure 6 shows the key drive unit during return to its upper inactive position.

Referring to Figure 1, the embodiment selected for illustration shows somewhat schematically certain of the parts of a conventional typewriter in cooperative relation with the power drive mechanism therefor of the present invention. The frame of the typewriter is indicated at 10, while the platen is shown at 11, this platen being mounted in the usual fashion on the traveling paper carriage, part of which is shown at 12. The conventional form of type bar is indicated at 13 which is operated through a linkage 14 from a dummy key bar or stem 16 referred to in greater detail hereinafter. The linkage 14 is also connected in a conventional manner to the usual escapement operating mechanism 17. This escapement mechanism is also operable through a space bar 18 of the usual character.

As shown, the typewriter 10 is suitably secured upon a base 21 which houses the power driven mechanism. The power driven mechanism includes a motor 22 which is suitably mounted in the base 21 and is connected by reducing gearing 23 to similar meshing gears 24 for a pair of rubber covered drive rolls 26 secured on respective shafts 27. The shafts 27 are suitably journaled at their ends in respective removable brackets 28, each bracket being secured to a similar supporting plate 29 suitably mounted on a wall of the casing 21. It will be seen that the rolls 26 are

driven as indicated by the adjacent arrows, the drive being constant when the motor is energized under control of its switch 31.

The constantly rotating rolls 26 are used to drive a series of normally expanded, but collapsible elements, each element forming part of a drive unit for an associated dummy key bar 16 as will now be described.

Referring to Figure 1, each dummy key bar 16 is similar in construction to the rearward end of conventional key bars of the typewriter, and as each of these dummy key bars and, in fact, the key drive unit for each of the typewriter keys, is similar, only one will be described. Each key bar 16 is guided adjacent its forward end in a comb 32 suitably secured to a cross bar 33 of the typewriter frame. Adjacent its rearward end the keybar 16 has a releasable, pivotal connection at 34 with a cross rod against which it is urged by a spring 36. The spring 36 maintains the forward end of the key bar 16 against a rubber bumper bar 37 having a yieldable mounting by means of one or more springs 38 below the cross bar 33 of the frame.

Referring to Figure 2, the key bar 16 is provided with a vertically extending slot 41 which is engaged by a stud 42 mounted in a vertically disposed plunger or auxiliary key stem 43. Stem 43 and key bar 16 are connected by a tension spring 44. The lower end of stem 43 is provided with a round extension 46 guided in a suitable aperture in a cross bar 47. Intermediate its ends the stem 43 is provided with a slot 51 which is engaged by a pin 52 carried by a key stem or bar 53 which has a releasable pivotal connection with a cross stud 54 (Figure 1) and is spring-urged in a clockwise direction by spring 56. The key stem 53 extends upwardly and through a guide comb 57 to provide a key 58 of the typewriter keyboard. Downward movement of key stems 53 is limited by means of a transverse stop bar 59 (Figure 1) suitably secured at its ends on the base 21.

As previously explained, the auxiliary key stem 43 (Figure 2) forms part of a normally expanded but collapsible means for drive by the rollers 26. For this purpose the key stem has pivoted thereon at 61 a normally expanded arm 62 having a tapered lower end 63 normally spaced from a flange 64 secured on the stem 43. The position of the expansion arm 62 is controlled by a cam 66 pivoted at 67 on the key stem 43. Cam 66 is normally urged in a clockwise direction as viewed in Figure 2 by a spring 68 to cause contact of the stop surface 69 of the cam with a stop pin 71 on the key stem 43. Spring 68 is tensioned between a pin on the cam 66 and the tail of a latching pawl 72 which is pivoted at 73 on the key stem 43. Pawl 72 has a pin and slot connection at 74 with the link 76 pivoted at 77 on the key bar 16.

Normally, the cam 66 is positioned as shown in Figure 2 with a full arcuate surface 81 thereof engaging the expansion arm 62 to hold it outwardly in expanded position against stop pin 82. In this position, the spacing between the arm 62 and the key stem flange 64 is wider than the spacing between the rolls 26.

Figure 3 illustrates the condition of the parts when the key 53 has been depressed a sufficient distance to move the pin 42 to the bottom of the slot 41 and slightly tension the spring 44. This movement is sufficient to engage the tapered lower end 63 of arm 62 with the adjacent roll 26 while the flange 64 is engaged with the opposite roller 26 so that the downward drive of the auxiliary key 43 of the key drive unit is begun.

Figure 4 illustrates the condition of the parts when the auxiliary key 43 has reached the bottom of its stroke. The downward movement of the key drive unit is stopped when an arcuate surface 83 of the cam 66 has engaged the cooperating roll 26 so that the cam 66 is in driving relation with such roll. With this condition of the parts, the cam 66 is driven in a counter-clockwise direction as viewed in Figure 4 from the position shown in Figure 4 to that shown in Figure 5 where an arcuate recess 84 of cam 66 is in registry with the roll 26 and the movement of the cam is stopped by engagement of shoulder 85 thereof with stop pin 71. During this movement a flat 86 on the cam 66 has come into cooperative relation with the expansion arm 62 to allow it to be retracted inwardly by the adjacent roller 26 so that there is a slight clearance between the collapsed elements of the plunger and the driving rolls 26 and the drive will cease. At the same time the cam 66 has been driven slightly beyond the point where the latch 72 can move into active position.

Figure 6 shows the parts as the return to top position has started under the influence of spring 36 (Figure 1). At this time cam 66 has been returned clockwise by spring 68 until its shoulder 69 engages the latching face of pawl 72 to hold the cam 66 in position where flat 86 engages arm 62 to maintain the collapsed condition of the key drive unit so long as the key 58 is maintained depressed. Upon release of the key 58, its spring 56 (Figure 1) becomes active to restore the parts to the condition shown in Figure 2. The rebound of the dummy key bar 16 from the bumper 37 is sufficient to act through the link 76 to disengage the latch pawl 72 from the shoulder of the cam and enable the cam 66 to turn under the influence of its spring to the position shown in Figure 2. This operation again moves arm 62 outwardly and provides an expanded condition of the key drive unit.

Briefly the operation of the power drive unit for the typewriter keys 58 is as follows: When the typist depresses a key 58 and its stem 53, the auxiliary key stem 43 is carried with the key stem 53 to tension the spring 44 and move the pin 42 to the bottom of the slot in the dummy key bar 16. This movement also engages the expansion arm 62 with its cooperating roll 26 so that a driving relation is established between the roll 26 and the operative key drive unit.

The rolls 26 carry the key drive unit downwardly from the position shown in Figure 3 to that shown in Figure 4 where the surface 83 of cam 66 engages the roll 26 and is driven thereby from the position shown in Figure 4 to the position shown in Figure 5. This movement of the cam 66 interrupts drive of the cam 66 by the

alignment of its arcuate recess 84 with the adjacent roll 26 and also interrupts the drive for the key drive unit by aligning the flat 86 of the cam 66 with the expansion arm 62 so that it can collapse. At the same time the latch 72 can become active to hold the cam 66 in the position shown in Figure 6 until return of the key drive unit to its upper inactive position. At this time the rebound of the dummy key bar 16 from its resilient stop 37 will operate through the link 76 to release the latch 72 so that the spring 68 can return the parts from the position shown in Figure 6 to that shown in Figure 2.

I claim:

1. In a power drive mechanism for a typewriter having a typebar, an operating bar operatively connected to said typebar to effect typing movement thereof, a drive unit connected to said operating bar, a pair of spaced-apart drive rolls for operating said drive unit, means for driving said rolls to cause adjacent surfaces thereof to travel downwardly, said drive unit comprising a plunger having a normally expanded, collapsible portion with a dimension when expanded greater than the spacing between said rolls, and said dimension being smaller than said spacing in the collapsed condition of said plunger, said portion being normally out of operative engagement with said rolls, and a key bar for moving said plunger to place said portion in driving relation with said rolls.

2. In a power drive mechanism for a typewriter having a typebar, a drive unit having a drive connection with said typebar, a pair of spaced-apart drive rolls for operating said drive unit, means for driving said rolls to cause adjacent surfaces thereof to travel downwardly, said drive unit comprising a plunger having a normally expanded, collapsible portion with a dimension when expanded greater than the spacing between said rolls, and said dimension being smaller than said spacing in the collapsed condition of said plunger, said portion being normally out of operative engagement with said rolls, and a key bar for moving said plunger to place said portion in driving relation with said rolls.

3. In a power drive mechanism for a typewriter having a typebar, a drive unit having a drive connection with said typebar, a pair of spaced-apart drive rolls for operating said drive unit, means for driving said rolls to cause adjacent surfaces thereof to travel downwardly, said drive unit comprising a plunger having a normally expanded, collapsible portion with a dimension when expanded greater than the spacing between said rolls, and said dimension being smaller than said spacing in the collapsed condition of said plunger, said portion being normally out of operative engagement with said rolls, means for moving said plunger to place said portion in driving relation with said rolls, and means carried by said plunger and operable by one of said rolls for causing collapsing of said portion near the end of the stroke of said plunger.

4. In a power drive mechanism for a typewriter having a typebar, a drive unit having a connection with said typebar, a pair of spaced-apart drive rolls for operating said drive unit, means for driving said rolls to cause adjacent surfaces thereof to travel downwardly, said drive unit comprising a plunger having a normally expanded, collapsible portion with a dimension when expanded greater than the spacing between said rolls, and said dimension being smaller than said spacing in the collapsed condition of said

plunger, said portion being normally out of operative engagement with said rolls, and a key bar for moving said plunger to place said portion in driving relation with said rolls, said key bar having a lost motion connection with said plunger to provide for independent movement of said plunger by said rolls after initial movement of said plunger by said key bar into engagement with said rolls.

5. In a power drive mechanism for a typewriter having a typebar, a drive unit having a drive connection with said typebar, a pair of spaced-apart drive rolls for operating said drive unit, means for driving said rolls to cause adjacent surfaces thereof to travel downwardly, said drive unit comprising a plunger having a normally expanded, collapsible portion with a dimension when expanded greater than the spacing between said rolls, and said dimension being smaller than said spacing in the collapsed condition of said plunger, said portion being normally out of operative engagement with said rolls, and a key bar for initially moving said plunger to place said plunger portion in driving relation with said rolls, a lost motion connection in said drive connection whereby said typebar does not move during said initial movement of said plunger by said key bar, said key bar having a lost motion connection with said plunger to provide for independent movement of said plunger by said rolls after initial movement of said plunger by said key bar into engagement with said rolls.

6. In a power drive mechanism for a typewriter having a typebar, an operating bar operatively connected to said typebar to effect typing movement thereof, a drive unit connected to said operating bar, a pair of spaced-apart drive rolls for operating said drive unit, means for driving said rolls to cause adjacent surfaces thereof to travel downwardly, said drive unit comprising a plunger having a normally expanded, collapsible portion with a dimension when expanded greater than the spacing between said rolls, and said dimension being smaller than said spacing in the collapsed condition of said plunger, said portion being normally out of operative engagement with said rolls, and a key bar for moving said plunger to place said plunger portion in driving relation with said rolls, said plunger having a lost motion connection with said operating bar whereby said operating bar does not move during said initial movement of said plunger by said key bar, said key bar having a lost motion connection with said plunger to provide for independent movement of said plunger by said rolls after initial movement of said plunger by said key bar into engagement with said rolls.

7. In a power drive mechanism for a typewriter having a typebar, a drive unit for said typebar, a pair of spaced-apart drive rolls for operating said drive unit, means for driving said rolls to cause adjacent surfaces thereof to travel downwardly, said drive unit comprising a plunger extending between said rolls and having a surface for engaging one of said rolls, an expanding arm movably mounted on said plunger for engagement with the other of said rolls and normally spaced from the same, and a cam on said plunger for controlling the position of said expanding arm relative to said plunger, said cam having a portion for holding said expanding arm

outwardly and a second portion to allow said arm to collapse toward said surface.

8. In a power drive mechanism for a typewriter having a typebar, a drive unit for said typebar, a pair of spaced-apart drive rolls for operating said drive unit, means for driving said rolls to cause adjacent surfaces thereof to travel downwardly, said drive unit comprising a plunger extending between said rolls and having a surface for engaging one of said rolls, an expanding arm movably mounted on said plunger for engagement with the other of said rolls and normally spaced from the same, a cam on said plunger for controlling the position of said expanding arm relative to said plunger, said cam having a position for holding said expanding arm outwardly and a second position to allow said arm to collapse toward said surface, and said cam being adapted to engage a roll at the bottom of the plunger stroke to be driven from said one position to said second position.

9. In a power drive mechanism for a typewriter having a typebar, a drive unit for said typebar, a pair of spaced-apart drive rolls for operating said drive unit, means for driving said rolls to cause adjacent surfaces thereof to travel downwardly, said drive unit comprising a plunger extending between said rolls and having a surface for engaging one of said rolls, an expanding arm movably mounted on said plunger for engagement with the other of said rolls and normally spaced from the same, a cam on said plunger for controlling the position of said expanding arm relative to said plunger, said cam having a position for holding said expanding arm outwardly and a second position to allow said arm to recede toward said surface, and said cam being adapted to engage a roll at the bottom of the plunger stroke to be driven from said one position to said second position, a latch for holding said cam in said second position, and means for causing release of said latch upon return of said drive unit to inactive position.

10. In a power drive mechanism for a typewriter having a typebar, an operating bar operatively connected to said typebar to effect typing movement thereof, a drive unit connected to said operating bar, a pair of spaced-apart drive rolls for operating said drive unit, means for driving said rolls to cause adjacent surfaces thereof to travel downwardly, said drive unit comprising a plunger extending between said rolls and having a surface for engaging one of said rolls, an expanding arm movably mounted on said plunger for engagement with the other of said rolls and normally spaced from the same, a cam on said plunger for controlling the position of said expanding arm relative to said plunger, said cam having a position for holding said expanding arm outwardly and a second position to allow said arm to recede toward said surface, and said cam being adapted to engage a roll at the bottom of the plunger stroke to be driven from said one position to said second position, a latch for holding said cam in said second position, a yieldable stop for said operating bar in the inactive position thereof, and a link extending from said operating bar to said latch to effect movement of said latch to an inactive position thereof upon return of said operating bar into engagement with said stop.
